Attorneys

UNITED STATES PATENT OFFICE.

HENRY E. DREVES, OF CLEVELAND, OHIO.

KEY MECHANISM.

Application filed July 21, 1926. Serial No. 123,880.

My invention relates to key assemblies for saxophones or the like, and particularly to means for supporting the keys from the key tubes, and the principal object of 5 my invention is to provide new and improved means of this type.

In saxophones and like instruments each key customarily comprises a facing of soft material such as leather arranged to engage 10 the opening in the instrument, and a metal backing or cup receiving and supporting this soft facing usually with additional soft material such as felt interposed between the facing and the cup; each 15 of these keys is customarily supported and operated by means of a lever connected at one end to the cup and at the other end to a tube fulcrumed on a single shaft which serves 20 as the fulcrum for a plurality of key assemblies; many of these tubes are interconnected to cause the keys connected thereto to operate in unison upon depression of a single finger piece, and every key is customarily permitted only a slight movement 25 away from the aperture in the instrument.

Under these circumstances it is ordinarily practically impossible to replace one of the facings without disassembling an appreciable part of the key mechanism and in addition, when a new facing is installed, it is 30 ordinarily impossible to adjust the various inter-connected key assemblies to provide for the increased thickness of the new facing in any way other than by bending the 35 parts.

My invention overcomes both of these difficulties.

In the drawings accompanying this specification and forming a part of this application I have shown, for purposes of illustration, several forms which my invention may assume. In these drawings:

Figure 1 is a cross-section through an instrument of the saxophone type showing one key assembly,

Figure 2 is a plan view of the key assembly shown in Figure 1,

Figure 3 is a view of the key assembly 40 portion of Figure 1 drawn on an enlarged

scale and showing a second form of my invention, while

Figures 4 through 7 are views similar to Figure 3 showing four additional forms 55 my invention may assume.

In this application I have shown my invention supporting, from a key supporting shaft 11 carried by brackets 12 secured to the instrument body 13, a key 14 comprising an intermediate felt member 15 to which 60 is secured a soft leather facing 16 arranged to close the opening 17 in the instrument body 13 by engagement with the rim 18 surrounding the opening 17, and a metal cup 19 to which the intermediate felt-soft 65 facing unit 15-16 is secured in any desirable manner, as by gluing.

In the embodiment of my invention shown in Figures 1 and 2 I have shown the key 14 supported from the key supporting 70 shaft 11 by means of a key lever 20 fixedly and permanently connected at one end to a key tube 21 fulcrumed on the key shaft 11, and quickly-detachably and adjustably connected at the other end to the key 14 by 75 means of a stud 22 rising from the outer face of the key cup 19, receiving the number of washers 23 necessary to provide the desired adjustment, then passing through an aperture 24 in that end of the key lever 80 20, and finally receiving a nut 25 effective to hold the pad 14 firmly and fixedly assembled on the key lever 20 in the desired adjusted position, yet readily separable 85 from the key lever 20 merely by removal of the nut 25.

In the embodiment of my invention shown in Figure 3 I have shown the pad 14 supported from the key shaft 11 by means of a key lever 30 fixedly and permanently 90 connected at one end to a key tube 31 fulcrumed on the key shaft 11, and quickly-detachably and adjustably connected at the other end to the key 14 by means of a cylindrical boss 32 rising from the outer face 95 of the key cup 19, receiving the number of washers 33 necessary to provide the desired adjustment, then passing through an aperture 34 in that end of the key lever 30, and provided centrally with a screw-threaded 100

aperture 35 arranged to receive a machine screw 36 effective to hold the key 14 firmly and fixedly assembled on the key lever 30 in the desired adjusted position, yet readily separable from the key lever 30 merely by removal of the machine screw 36.

In the embodiment of my invention shown in Figure 4 I have shown the key 14 supported from the key shaft 11 by means 10 of the key lever 40 fixedly and permanently connected at one end of a key tube 41 fulcrumed on the key shaft 11, and quickly-detachably and adjustably connected at the other end to the key 14 by means of a stud 15 42 rising from the outer face of the key cup 19, receiving the number of washers 43 necessary to provide the desired adjustment, then passing through an aperture 44 in that end of the key lever 40, and finally receiving 20 a nut 45, the face of the nut 45 engaging the key lever 40, the face of the cup 19 engaging the key lever 40 when the washers 43 are omitted, and the washers 43, being all formed convex, and the engaged portions of 25 the key lever 40 being formed concave, to permit swiveling of the key 14 on the lever 40 to permit the key 14 to seat uniformly despite minor inaccuracies, the nut 45 holding the key 14 assembled on the key lever 40 30 in the desired adjusted position, either for free angular movement from time to time or, by tightening of the nut 45, in fixed angular position, and the key 14 being still readily separable from the key lever 40 merely by removal of the nut 45.

In the embodiment of my invention shown in Figure 5 I have shown the key 14 supported from the key shaft 11 by means of a key lever 50 fixedly and permanently 40 connected at one end to the key tube 51, and fixedly and permanently connected at the other end to the key cup 19, but formed in two parts 52 and 53 connected by means of a securing bolt 54 and with the interposition 45 of the number of washers 55 necessary to provide the desired adjustment, the bolt 54 thus being effective to hold the key 14 firmly and fixedly assembled on the lever section 52 in any desired adjusted position, 50 yet readily separable from the lever section 52 merely by removal of the bolt 54.

In the embodiment of my invention shown in Figure 6 I have shown the key 14 supported from the key supporting shaft 11 55 by means of a key lever 60 fixedly and permanently connected at one end to a key tube 61 fulcrumed on the key shaft 11, and quickly-detachably and adjustably connected at the other end to the key 14 by means of a 60 stud 62 rising from the outer face of the key cup 19, receiving the number of washers 63 necessary to provide the desired adjustment, then passing through an aperture 64 in that end of the key lever 60, and finally receiving 65 a nut 65 effective to hold the key 14 firmly

and fixedly assembled on the key lever 60 in the desired adjusted position, held against rotation relative to the key lever 60 by means of pins 66 inserted into cooperating recesses in the stud 65 and the key lever 60, yet 70 readily separable from the key lever 60 merely by removal of the pins 66 and the nut 65.

In the embodiment of my invention shown in Figure 7 I have shown the key 14 supported from the key shaft 11 by means 75 of a key lever 70 fixedly and permanently connected at one end to a key tube 71 fulcrumed on the shaft 11, and quickly-detachably and adjustably connected at the other end to the key 14 by means of a stud 72 rising from the outer face of the key cup 19, receiving the number of washers 73 necessary to provide the desired adjustment, then passing through an aperture 74 in that end 80 of the key lever 70, and finally receiving a nut 75 effective to hold the key 14 firmly and fixedly assembled on the key lever 70 in the desired adjusted position, held against rotation relative to the key lever 70 by the square cross-section of the aperture 74 in the lever 70 and of the cooperating portion of the stud 72, yet readily separable from the key lever 70 merely by removal of the nut 75.

It will of course be obvious to those skilled in the art that the angular adjustment provided in the embodiment of Figure 4 may be provided in any of the other embodiments shown herein, and that the detention against rotation present in the embodiments of Figures 6 and 7 may be employed in connection 100 with any of the other embodiments herein shown.

At the same time it will also be obvious to those skilled in the art that the embodiments of my invention herein shown and described do accomplish the principal purpose of my invention, and also that these embodiments may all be variously changed and modified without departing from the spirit of my invention or sacrificing the advantages thereof. 110

Under these circumstances it will be understood that the disclosure herein is illustrative only and that my invention is not limited thereto.

I claim:

1. A key assembly, for a saxophone or the like, comprising a key shaft, a key tube fulcrumed on said key shaft, a key, and lever means extending from said key tube and quickly-detachably connected to said key 120 quickly-detachably supporting said key from said key tube.

2. A key assembly, for a saxophone or the like, comprising a key shaft, a key tube fulcrumed on said key shaft, a key, and lever means extending from said key tube and adjustably connected to said key adjustably supporting said key from said key tube. 125

3. A key assembly, for a saxophone or the like, comprising a key shaft, a key tube ful- 130

- erumed on said key shaft, a key, and lever means extending from said key tube and supporting said key from said key tube universally movable relative to said key tube to insure seating of said key. 5
4. A key assembly, for a saxophone or the like, comprising a key shaft, a key tube fulcrumed on said key shaft, a key, and lever means extending from said key tube and quickly-detachably and adjustably connected to said key quickly-detachably and adjustably supporting said key from said key tube. 10
5. A key assembly, for a saxophone or the like, comprising a key shaft, a key tube fulcrumed on said key shaft, a key, and lever means extending from said key tube and quickly-detachably connected to said key quickly-detachably supporting said key from said key tube universally movable relative to said key tube to insure seating of said key. 15
6. A key assembly, for a saxophone or the like, comprising a key shaft, a key tube fulcrumed on said key shaft, a key, and lever means extending from said key tube and adjustably connected to said key adjustably supporting said key from said key tube universally movable relative to said key tube to insure seating of said key. 20
7. A key assembly, for a saxophone or the like, comprising a key shaft, a key tube fulcrumed on said key shaft, a key, and lever means extending from said key tube and quickly-detachably and adjustably connected to said key quickly-detachably and adjustably supporting said key from said key tube universally movable relative to said key tube to insure seating of said key. 25
8. A key assembly, for a saxophone or the like, comprising a key shaft, a key tube fulcrumed on said key shaft, a key, and lever means extending from said key tube and quickly-detachably connected to said key quickly-detachably supporting said key from said key tube non-rotatable about the axis of said key. 30
9. A key assembly, for a saxophone or the like, comprising a key shaft, a key tube fulcrumed on said key shaft, a key and lever means extending from said key tube and adjustably connected to said key adjustably supporting said key from said key tube non-rotatable about the axis of said key. 35
10. A key assembly, for a saxophone or the like, comprising a key shaft, a key tube fulcrumed on said key shaft, a key, and lever means extending from said key tube and supporting said key from said key tube non-rotatable about the axis of said key but universally movable relative to said key tube to insure seating of said key. 40
11. A key assembly, for a saxophone or the like, comprising a key shaft, a key tube fulcrumed on said key shaft, a key, and lever means extending from said key tube and quickly-detachably and adjustably connected to said key quickly-detachably supporting said key from said key tube non-rotatable about the axis of said key. 45
- means extending from said key tube and quickly-detachably and adjustably connected to said key quickly-detachably and adjustably supporting said key from said key tube non-rotatable about the axis of said key. 70
12. A key assembly, for a saxophone or the like, comprising a key shaft, a key tube fulcrumed on said key shaft, a key, and lever means extending from said key tube and quickly-detachably connected to said key quickly-detachably supporting said key from said key tube non-rotatable about the axis of said key but universally movable relative to said key tube to insure seating of said key. 75
13. A key assembly, for a saxophone or the like, comprising a key shaft, a key tube fulcrumed on said key shaft, a key, and lever means extending from said key tube and adjustably connected to said key adjustably supporting said key from said key tube non-rotatable about the axis of said key but universally movable relative to said key tube to insure seating of said key. 80
14. A key assembly, for a saxophone or the like, comprising a key shaft, a key tube fulcrumed on said key shaft, a key, and lever means extending from said key tube and quickly-detachably and adjustably connected to said key quickly-detachably and adjustably supporting said key from said key tube non-rotatable about the axis of said key but universally movable relative to said key tube to insure seating of said key. 85
- In testimony whereof I hereunto affix my signature. 90

CERTIFICATE OF CORRECTION.

Patent No. 1,727,868.

Granted September 10, 1929, to

HENRY E. DREVES.

It is hereby certified that error appears in the printed specification of the above numbered patent requiring correction as follows: Page 1, line 23, strike out the comma and insert a semi-colon, and lines 82 and 88, for "pad 14" read "key 14"; page 3, line 50, claim 9, after the word "key" second occurrence, insert a comma; and that the said Letters Patent should be read with these corrections therein that the same may conform to the record of the case in the Patent Office.

Signed and sealed this 15th day of October, A. D. 1929.

M. J. Moore,
Acting Commissioner of Patents.
